(57) **CLAIM**

The ornamental design for holder, as shown and described.

DESCRIPTION

FIG. 1 is a top perspective view of a holder, showing my new design;

FIG. 2 is a top perspective view thereof, shown in an alternate configuration;

FIG. 3 is a top perspective view of the holder of FIG. 1, showing an unclaimed secondary support arm;

FIG. 4 is a top perspective view of the holder of FIG. 1, showing an alternate configuration and unclaimed secondary support arm to that shown in FIG. 3;

FIG. 5 is a side elevation view of the holder of FIG. 1, showing two unclaimed support arms.

FIG. 6 is the opposing side elevation view thereof.

FIG. 7 is a top plan view thereof, shown at a reduced scale; and,

FIG. 8 is a top perspective view of the holder of FIG. 1, shown in use.

In FIGS. 1–8, the broken line showing of the holder mid-shaft, the relative size and shape of the detachable secondary arm, and the shape of the foot plate are for illustrating portions of the article and form no part of the claimed design.

In FIG. 8, the broken line showing of the beverage can is for the purpose of illustrating environmental structure and forms no part of the claimed design.
